CLAIM

The ornamental design for a tape measure device, as shown and described.

DESCRIPTION

FIG. 1 is top, front and right side perspective of a tape measure device, in this view with a tape measure extended from the device;

FIG. 2 is a side view, seen from a right side, of the tape measure device shown in FIG. 1, in this view with the tape measure retracted into the device;

FIG. 3 is a side view, seen from a left side, of the tape measurement device of FIG. 1, in this view with the tape measure retracted into the device;

FIG. 4 is a back view of the tape measure device of FIG. 1; FIG. 5 is a front view of the tape measure device of FIG. 1, in this view with the tape measure retracted into the device; FIG. 6 is a bottom view the tape measure device of FIG. 1, in this view with the tape measure retracted into the device; and,

FIG. 7 is a top view the tape measure device of FIG. 1, in this view once again with the tape measure retracted into the device.

The characteristic feature of the design resides in the overall appearance of the tape measure device.

Broken lines in FIGS. 1-7 depict elements that are not part of the subject design.

1 Claim, 6 Drawing Sheets
